UNITED STATES PATENT OFFICE.

SAMUEL LIPPERT, OF CLEVELAND, OHIO.

WELL PUMPING AND PULLING DEVICE.

No. 853,180.

Specification of Letters Patent.

Patented May 7, 1907.

Application filed May 15, 1905. Serial No. 260,369.

To all whom it may concern:

Be it known that I, SAMUEL LIPPERT, a citizen of the United States, and a resident of Cleveland, county of Cuyahoga, State of Ohio, have invented certain new and useful Improvements in Well Pumping and Pulling Devices, of which I hereby declare the following to be a full, clear, and exact description, such as will enable others skilled in the art to 10 which it appertains to make and use the same.

The object of the invention is to operate all, or any one or more of a large number of wells, in a given locality, by working the 15 pumps at or in such wells, by means of individual motors operated by electricity from one or more sources of power, at points in such locality where the electric current can be most conveniently generated; whereby 20 any one or more of such wells can be operated separately or in connection with any or all such wells at any time, and from time to time and each well can be operated independently at such time and for such periods as may be 25 necessary or expedient with or without requiring the operation of any other well in such locality, and without in any way interfering with the operation of any other well in such locality, and the wells operated from a 30 single source of power are limited in number only by the amount of power generated, and in location only by the distance to which the electric current can be transmitted irrespec- 35 tive of the broken, rugged or mountainous character of the country.

The invention is particularly applicable to the pumping of wells in oil fields, where in a rugged country they could only be pumped singly or in very small numbers, and in a level 40 country not more than twenty or thirty wells can be operated from one source of power.

In the present system the pumping devices in a field of oil wells, are all connected together and a sufficient number of wells must 45 be operated at once and kept in connection by shackle rods with the power to balance it in all directions. Again if a well is too far removed from the source of power it must be abandoned until the power, which is of a me- 50 chanical kind can be moved nearer to it, for the reason that sufficient lost motion is caused to prevent operating the distant wells. On account of this objection, hundreds of good producing wells have been abandoned.

55 In a field of oil wells a large number of them are only fair producers, and to operate

economically, it is necessary that all the wells should be pumped simultaneously to obtain a maximum production of oil, and requisite balance of power, which is difficult to provide 60 for by purely mechanical means, with widely scattered wells. Furthermore mechanical connections between the wells distributed over the surface of the ground, greatly interfere with farming operations and with shackle 65 rod posts 16 or 20 feet apart, cover the available tillage surface.

My invention is designed to overcome all these objectionable features and by means of utilizing the electric current as a motive 70 power and an individual motor device for each well, to accomplish more than can be done in a mechanical way, without disturbing or encumbering the land for farm uses. The further objectionable features of great 75 waste of power absorbed in friction, and unnecessary mechanical connections extending from well to well over the ground, are also avoided, and greater efficiency and practicability obtained at less expense in material 80 and labor, than by mechanically connected devices. I also obtain these advantages by means of an electrically operated motor for each well, and automatically operating apparatus driven by the motor which can be readily applied to the pump rod and casing of an ordinary oil well, with comparatively little 85 change of the permanent parts already installed in place.

The invention consists in the driving gears, 90 adapted to give a longitudinal movement to the pump rod or "polish rod" and in the various devices for changing a direct to a reciprocating movement thereof, and in the combination and arrangement of parts and construction of details as hereinafter described, 95 shown in the accompanying drawings and specifically pointed out in the claims.

In the accompanying drawings Figure 1 is 100 a vertical elevation in section of the casing head of a well, showing an end view of the miter change gears, and operating nut and pinion, and screw threaded sleeve upon the polish rod, and also the shifting rod by means of which a reciprocating movement is 105 obtained for the polish rod; Fig. 2 is a similar elevation showing a side view of miter change gears, the motor and motor shaft, and end view of hoisting drum; Fig. 3 is a detail vertical section on line of vertical driving 110 shaft, showing shifting rod and reversing mechanism, Fig. 4 is a plan view of the de-

vice, in horizontal section above reversing gears; and Fig. 5 is a perspective view of the device arranged to "pull" the pumping rods.

5 In these views 1 is the well tubing, 2 the casing, 3 the casing head, 4 the cap for the casing head, 5 the stuffing box, and 6 the polish rod, which is coupled to the sucker rod 7 inside the well tubing. These parts are permanently employed in all oil wells and remain practically unchanged.

The attached parts for operating the well comprise the motor 8 and provided with a shaft 9 upon which are loosely sleeved the miter gears 10 and 11 spaced apart to include between them the friction cones 12 and 13, which engage alternately with conical recesses in the inner faces of the miter gears. A central clutch 14 and clutch lever 15 serve to alternately engage these cones and gears. Above these gears 10 and 11 and engaging with them is the miter gear 16 upon the vertical shaft 17, upon the upper extremity of which is secured a pinion 18. The vertical shaft 17 is closely adjacent to the polish rod 6. Upon the polish rod at the upper end is tightly secured the sleeve 19 which is screw threaded, and upon the threaded sleeve is mounted the spur gear 21 which is internally threaded to provide a nut through which the sleeve moves longitudinally. This gear nut, intermeshes with the pinion 18 and is driven thereby. In this manner a reciprocating movement is given to the polish rod since by rapid revolution in one direction the nut will raise the sleeve to the limit of the stroke, and by the reverse movement of the nut the sleeve will be lowered to the length of the stroke. This alternating movement is constantly repeated by means of a shifting device controlled by an arm upon the polish rod so as to throw the clutch and reverse the miter gear movement at the end of each pump stroke. This shifting mechanism may be described as follows: The clutch lever 15 is moved to alternately engage the friction cones 12 or 13 on the clutch sleeve 14 with the miter gears 10 and 11 by means of any convenient automatic device mechanically connected with the polish shaft.

The particular form of device shown consists of a vertical shifting rod 22, adjacent to the polish rod, and provided with buttons 23 adjustably secured thereon. This rod is balanced so as not to fall by its own weight by means of the pedestal spring 24 at the lower end. An arm 25 adjustably fixed upon the polish rod so as to regulate the length of the stroke engages these buttons and moves the rod to shift the clutch.

Intermediate mechanism to accomplish this purpose is shown to consist of a tilting shaft 26 adapted to rotate in a sleeve 27 which is pivoted upon the clutch lever 15. This shaft is pivoted at one end at 28 to the

shifting rod 22, and is provided with friction rollers 29 and 30 which engage in turn with a horizontal disk 31 as the end of the shaft affixed to the shifting rod is raised or lowered. This disk is driven by means of a vertical disk 32 secured upon the clutch sleeve 14. Thus a rapid rotary movement is given the shaft 26. At the outer end of this shaft is shown a screw 33, and a nut 34 thereon. A bell crank 35 and link 36 connect this nut 34 with the outer end of the clutch lever 15. The action of this device is simple and efficient when the shifting rod is lowered it lowers the inner end of the small shaft 26, and brings the friction roller 29 into engagement with the always rotating disk 31, this rotates the shaft 26 in one direction. The nut 34 moves upon the screw 33 and the bell crank pulls the clutch lever 15 to engage one of the cones of the clutch with one of the reversing gears.

When the shifting rod is raised the friction roller 30 engages the disk 31 on the opposite side of the center thereof, the small shaft 26 is rotated in the other direction. The screw 33 moves the nut and bell crank in the opposite direction and the clutch lever is thrown to bring the other cone into engagement with the second reversing gear. Since the shaft 26 must be flexible to permit of lifting and lowering the end attached to the shifting rod, the shaft is divided and toggles 35 and 36 and a sleeved portion 37 are employed to give freedom of movement. A bearing 38 supports the outer end of the shaft. The disk 31 is vertically adjustable by means of the set screw 39 beneath it. In this manner the reversal of the miter gears 10 and 11 to change the direction of travel of the pumping rod is controlled automatically by the rod itself.

It is of course of important that the pump and polish rods should not turn as the gear nut turns upon the sleeve screw, hence to avoid all possibility of such a mishap, the arms 35' are secured to the extremities of the screw sleeve, and vertical rods 36' connect them. These rods pass through guides 37' upon the frame 38' of the machine.

To obtain simplicity of construction and applicability of the device to any well, the frame 38' and the motor and miter gearing are all mounted upon the platform 39 which can be as shown secured to or integral with the cap 4 of the well casing head. Hence all parts of the device are compact and portable and can be readily placed in position wherever the location of the well may be.

A field of wells, each provided with the above described apparatus can be connected by means of circuit wires with a central or more distant power station, and operated singly or in unison until exhausted, without dependence upon one another, and without disarranging the balance of the power in any

way, if some of the wells become exhausted previously to exhausting all of them.

An important feature of the invention is shown in the hoisting windlass 41 geared to the pinion 42 upon the motor shaft. The object of which is to provide means for hoisting the sucker rods or tubing out of the well or for pulling the well as it is turned. This operation has heretofore required separate apparatus laboriously brought to the well, involving much loss of time and labor, but with the power directly applied to each well, the operation of "pulling" it requires little time and labor. The hoisting rope can be attached to any convenient gin pole or derrick, not forming a feature of this invention.

For convenience in "pulling" the frame of the machine is hinged at 44 so that the upper portion can be folded back after removing the screw sleeve and gear nut, and pinion and loosening the stay rod 45, after which the tubing or rods can be readily pulled. A clutch 46 and lever 47 is used to throw the pinion 42 into engagement with the gear 48 upon the windlass shaft 49, and a brake 50 is shown to control the hoisting drum.

The entire machine is compact and especially suited to the peculiar uses of the oil field. Its use for pulling rods or tubing is graphically illustrated in Fig. 5 where the upper portion of the frame is shown thrown

back to release the tubing, and a gin pole 51 is raised with which to pull the tubing. Here the rope 52 wound around the drum, is shown passed over pulleys 53 and 54, and over pulley 55 at the top of the gin pole. The end is then attached in the usual manner by grappling tongs 56 to the tubing. Heretofore horse power has been employed for this purpose and from the construction of the devices employed many men and horses have been killed.

I claim:

The combination with the casing, tubing and pumping rod of a well of a platform secured to said casing, a motor and shaft thereon, a hoisting drum on the platform, geared connections with said drum and motor shaft, a frame upon the platform through the upper portion, of which the pumping rod passes, driving mechanism operatively and automatically connecting the movements of the pumping rod, and motor shaft the said frame being hinged for temporary removal from engagement with said pumping rod, substantially as described.

In testimony whereof I affix my hand this 12th day of May 1905.

SAMUEL LIPPERT.
